UNITED STATES PATENT OFFICE.

JAMES NOLAN, OF DETROIT, MICHIGAN, ASSIGNOR OF ONE-HALF TO JOHN G. CRAIG, OF SAME PLACE.

STOCK-CAR FOR TRANSPORTING POULTRY.

SPECIFICATION forming part of Letters Patent No. 425,242, dated April 8, 1890.

Application filed July 1, 1889. Serial No. 316,178. (No model.)

To all whom it may concern:

Be it known that I, JAMES NOLAN, a citizen of the United States, residing at Detroit, in the county of Wayne and State of Michigan, 5 have invented certain new and useful Improvements in Stock-Cars for Transporting Live Poultry, of which the following is a specification, reference being had therein to the accompanying drawings.

10 This invention relates to new and useful improvements in stock-cars especially designed for the transportation of poultry; and the invention consists in the peculiar construction, arrangement, and combination of 15 the parts, all as more fully hereinafter described, and shown in the accompanying drawings, in which—

Figure 1 is a side elevation of a portion of the car. Fig. 2 is a diagram plan thereof. 20 Fig. 3 is an enlarged plan of one end of the car. Fig. 4 is a vertical longitudinal section on line xx in Fig. 2. Fig. 5 is a cross-section of the car. Fig. 6 is a detached side elevation of the feed-bin. Fig. 7 is a detached side elevation of the water-tank. Fig. 8 is a cross-section of the feed-bin. Fig. 9 is an enlarged 25 detached detail of the mechanism for pressing the sliding covers against the side walls of the car. Figs. 10 and 11 are detail elevations showing the constructions of the upper and lower ends, respectively, of the swinging stanchions. Fig. 12 is a perspective view of 30 one of the coops. Fig. 13 is a detached elevation of one of the sliding slats of the coops.

35 The car-body A is preferably constructed as in the cars used for the transportation of merchandise—that is, inclosed upon all sides and provided with doors B in the center of each side.

40 The ends of the car-body are preferably unprovided with platforms, but have windows or doors C, mainly used for the purpose of ventilating the interior, and ventilating-caps D for the same purpose are preferably fixed 45 through the roof of the car. The sheathing inclosing the car-body on the sides is secured to the frame of the car upon the inside, and is provided its whole length, or nearly so, with numerous openings or perforations E, 50 preferably arranged in vertical rows between the roof and the floor of the car. On the in-

side sliding doors or shutters F, provided with openings G, are placed close to the side walls to open or close the openings, according to the state of the atmosphere or the need of 55 ventilation. The shutters are preferably suspended by hangers F', which carry grooved rollers F'' from a rail F³, secured overhead to the side walls, and the shutters are connected for joint operation, such as shown in the 60 drawings, where bars F⁴ are longitudinally secured to each series of contiguous shutters, and pinions F⁵, suitably mounted in the corners of the car, engage into racks F⁶, whereby, in turning each pinion by means of a crank, 65 the whole series of sliding shutters are moved together. The shutters can thus be readily moved into any desired position to either exclude or admit the outside air in any desired degree to the interior of the car as required 70 for the perfect comfort and maintenance of good sanitary conditions.

To prevent the shutter from rattling when the cars are in motion, suitable devices are employed, such as rock-shaft H, journaled in 75 suitable bearings on the floor of the car in proximity to the shutters. At suitable intervals eccentric portions H' are provided or formed on this shaft, which, when the shaft is turned into a certain position, are adapted 80 to bear against the lower end of the shutters and thereby crowd them against the side walls of the car. To this end a lever H² is conveniently secured and properly connected to the shaft H, as by means of the rod H³ and 85 rock-arm H⁴, all so arranged that by moving the lever H² in the proper direction the rock-shaft will lock or unlock the shutters with its eccentric portions.

To get the rock-shaft H out of the way, I 80 preferably secure to the lower end of each shutter an angle-plate H⁵, as shown in Fig. 9. The dependent part of this plate, being close to the side wall of the car, affords the necessary room to secure the rock-shaft H directly 95 underneath the shutters, where it is out of the way.

The interior of the car is provided with vertical stanchions I, adapted to fold closely against the sides of the car when not in use, 100 and when turned at right angles thereto and locked in position to form a partition to hold

the coops J in place. I preferably construct the stanchions in the form of a skeleton frame of gas-pipe, as shown in Figs. 5, 10, and 11, where *a* and *b* are two vertical members and 5 *c* horizontal members, which are secured to the vertical members. The vertical member *a* turns in vertical bearings *e*, secured to the side walls of the car, in which it is also free to slide vertically, and the vertical member *b* 10 extends with its ends into proximity to the roof and floor of the car, and is adapted to be engaged at its upper end with a locking-sleeve *f*, slidably sleeved on a stud *g*, which projects from the roof of the car, while the 15 lower end of the member *b* is adapted to engage coincidentally with a step *h*, formed on the floor of the car. As the stanchions are of lesser width than the distance at which they are placed apart, they may be folded 20 close against the sides of the car entirely out of the way, and if turned at right angles to the sides of the car they can be firmly locked in place.

The coops are substantially of known construction, being formed with slats or boards with open spaces between upon all sides and upon top, with a close bottom, a close division-wall through the middle, and a movable slat *i* in the front of each compartment for suitable access. The coops are constructed in a substantial manner and are preferably bound with iron straps *j*.

The object of the stanchions is to hold the coops J in position against displacement by 25 the motion of the car. To this end the stanchions are just far enough apart to allow the coops to be placed between the stanchions. In the drawings the dimensions are 30 such as to place six coops conveniently on top of each other between the stanchions. To hold them in place, I form projections *J'* on the ends of the coops, which projections are adapted to engage back of the central vertical members *b* of the stanchions, as 35 shown in Fig. 3, whereby the coops are prevented from displacement against the center of the car, while no end motion can take place as the stanchions are locked in position. The 40 projections *J'* on the coops may be formed by merely securing two blocks of wood to the 45 ends of each coop and by placing one at the bottom at one end and the other at the other end near the top. The coops can be made to fit between the stanchions without interfering 50 with the blocks or projections *J'* of the adjoining coops, thus utilizing all the space and bringing all the coops in actual contact with each other, so that the strain caused by 55 the tendency of longitudinal displacement 60 when the car is in transit need not be sustained entirely by the stanchions. The depth of the coops is calculated to leave when the car is loaded an aisle K in the center of the car, which is of sufficient width for the attendant to attend to his work of feeding and 65 watering the poultry, which is effected by means of the sliding doors or slats *i*, which, as

shown in Fig. 2, are arranged at different heights in the different compartments of each coop, and so that they can be slid back toward the center without interfering with each other. A simple locking device is provided for each sliding slat by providing it with a horizontal slot *i'*, terminating in a vertical portion *i''* and engaging with a pin *i'''* in the 70 housing of the inner ends of the slats. The manner of opening and closing these sliding slats is self-evident.

The provisions made for carrying food and water consist of a water-tank L, preferably of 75 tubular shape, suspended in the center of the roof in one end or half of the car. This tank has a suitable fill-opening L' in the top, and one or more discharge-openings L'', controlled 80 by valves in the bottom, for the convenient distribution of the water into the coops by means of a flexible hose attached thereto. To prevent freezing, or to take the chill off the water in cold weather, I preferably arrange a little heating-drum outside the tank 85 and communicating therewith through a system of circulating-pipes L⁵, and underneath this heater I place a suitable source of heat, such as the oil-stove L⁶. By this means the water in the tank L circulates through the heater 90 L⁴ and may be kept from freezing. The food is kept in a bin M, suspended in a similar manner as the water-tank in the center of the roof of the car in the other half or end of the car. This bin is preferably hopper-shaped in cross-section, as shown in Figs. 5 and 8, and is provided at the under side with one or more sliding doors M' for letting out the grain or other food contained therein in such quantities as wanted for use, and one or more openings M² 95 are provided in the top for filling the bin from the outside.

It will be seen that my construction embodies great simplicity in all its various details, and comprises all the facilities for the 100 safe and convenient transportation of poultry and kindred stock. To some of the features of my construction I desire to call special attention as embodying the principal parts of my invention.

In transporting poultry the most careful attention is necessary as to ventilation, as while the poultry need plenty of fresh air they are nevertheless very susceptible to exposure in hot, cold, or inclement weather, and 105 constant losses are incurred in shipment either by too much exposure or from a lack of fresh air. Now, with my construction a plentiful supply of fresh air may be admitted directly into each coop through the side walls 110 of the car, and a circulation of air is maintained through the coops, into the aisle, and out through the ventilation in the roof. If the wind blows too strong against one side of the car, the ingress of air on this side may be 115 reduced or altogether cut off. In inclement weather the openings in the sides of the car may be partially or altogether closed and sufficient ventilation secured by opening at in-

5 tervals or through the openings at the ends of the car. Thus no contingency of weather can arise in which suitable provisions cannot be made for providing sufficient and ample 10 ventilation without exposure. The provisions made for preventing the shutter from rattling also serve the purpose of keeping out the air when the shutters are closed, and the devices provided for adjusting the shutters reduce 15 the work to a minimum.

10 An important advantage is secured in my construction as regards the loading and unloading of the cars. With coops or stalls of a 15 stationary nature the loading and unloading 20 of the car consumes a great deal of valuable time and delays the use of the cars. With 25 my construction the loading is accomplished in a small fraction of time, as the coops may be kept all ready, with the poultry in, to be 30 carried into the car as fast as they can be put 35 in place, which consumes but little time, as the loading may be proceeded with from the four corners of the car simultaneously toward 40 the middle. The stanchions, being all folded 45 against the sides, are out of the way, until 50 they are one after another turned into position as the vertical rows of coops are piled up. The unloading is proceeded with from the 55 middle toward the ends, and the coops are 60 carried out with the poultry in them, the 65 stanchions being folded out of the way as 70 soon as they are free to fold.

75 The construction and arrangement of the parts afford the greatest possible economy 80 of space, as the whole interior of the car is utilized, except the necessary space for an attendant to move around, and if the openings in the side walls are made sufficiently numerous and large plenty of light is obtained 85 90 through them without the expense of windows.

95 The stanchions, as will be seen, form little or no obstruction inside of the car when folded against the side walls, and thus the car is 100 available for ordinary uses in transporting freight. When extended between the coops they project only about half the depth of the coops, and form no obstruction to the light or air, and by securing the stanchions to a vertical upright, fastened to the side walls between the sliding shutters, an abutment is provided for the rear end of the coops to prevent the coops from coming in contact with the shutters.

105 55 What I claim as my invention is—

110 1. In a stock-car, the combination, with a car-body having openings or perforations in the side walls, of inside sliding shutters suspended by hangers, overhead rails on which 115 the hangers are placed, and of rock-shafts journalized in the car-floor, said rock-shafts having eccentrics thereon, whereby they are adapted to hold the shutters against the side walls, as described.

120 65 2. In a stock-car, the combination of side walls having openings or perforations, the inside sliding shutters applied thereto, over-

125 head rails on which the shutters are suspended, the central bars connecting them in series, and the rack-bar and pinion device 70 applied thereto to simultaneously control each series of shutters from the ends of the car on the inside, substantially as described.

75 3. In a stock-car, the combination of the side walls having openings or perforations, 80 the inside sliding shutters applied thereto to control the admission of air, overhead rails on which the shutters are suspended through said openings, the bars connecting the shutters in series, the rack and pinions device for 85 simultaneously controlling each series of shutters, and the rock-shafts journalized in proximity to the sliding shutters and provided with eccentric portions or projections adapted to crowd the shutters against the side walls, substantially as described.

90 4. In a stock-car, the combination of the side walls having openings or apertures, inside sliding shutters connected in series for joint operation to control the admission of air 95 through said openings or perforations, overhead rails on which the shutters are suspended, angle-bars secured to the lower ends of the sliding shutters, and rock-shafts—one for each connected series of shutters—journalized near the car-floor below the sliding 100 shutters and provided with eccentrics or projections adapted to bear against the dependent flanges of the angle-bars, and means for operating the rock-shaft, substantially as described.

105 5. The combination, with the car-body having the perforated side walls provided with doors in the center thereof, of the sliding inside shutters F, connected in series on opposite sides of the door for joint adjustment to control the admission of air through the openings in the side walls, the hangers F' and rail F, from which the shutters are suspended, the angle-bars H⁶, secured to the lower ends of 110 the shutters, the rock-shaft H, journalized below the shutters and provided with eccentric portions or projections H', and the lever H² and its operating-connection with the rock-shaft H, substantially as described.

115 6. The combination of the car-body having its longitudinal side walls constructed of an outer frame and a perforated sheathing applied to the inside thereof, doors formed in the center of said side walls, shutters F, slidingly suspended from the top of the side walls and provided with openings G, adapted to register with the perforations in the side walls, horizontal bars F⁴, connecting the contiguous series of shutters on opposite sides of 120 the doors and extending into the corners of the car, and the rack and pinion device F⁵ and F⁶, applied thereto to jointly operate each series of shutters from the inside of the car, substantially as described.

125 7. In a stock-car, the combination, with independent coops adapted to be placed in vertical rows on top of each other along the side walls of the car-body, of swinging frames for 130

- holding the vertical rows of coops in place, said frames being hinged to the side walls of the car to be folded against said side walls or to be extended at right angles thereto, and of 5 locking devices applied thereto to lock them in position when thus extended, substantially as described.
8. In a stock-car, the combination, with the car-body, of vertical folding frames or stanchions, each consisting of a vertical member *a*, hinged to the side walls, the cross-bars *c*, and the vertical member *b*, secured thereto, and the step *h* and locking-sleeve *f*, with which 10 said vertical member is adapted to engage in the extended position of the stanchion, substantially as described.
9. In a stock-car, the combination, with the car-body, of vertical folding frames or stanchions hinged to the side walls thereof and 15 adapted to be extended at right angles thereto and locked in position, and independent coops having end projections adapted to fit between said stanchions and engage therewith to prevent longitudinal and lateral displacement, substantially as described.
10. In a stock-car, the combination, with the car-body, of vertical folding frames or stanchions, each consisting of a vertical member *a*, hinged to and supported in vertical 20 bearings on the side wall, the cross-bars *c*, extending therefrom, and a vertical member *b*, secured to said cross-bars, of the step *h* and sliding sleeve *f*, forming a locking device for the vertical member *b* of the stanchion, and 25 of the coops *J*, adapted to fit between the stanchions and having the projections *J'* at

the opposite ends, one near the bottom and the other near the top, substantially as described.

11. In a stock-car, the combination, with 40 the car-body, of a water-reservoir secured to the roof of the car and provided with fill and discharge openings, of a heater *L*⁴, connected thereto by a system of circulating-pipes *L*⁵, and the lamp or stove *L*⁶ to heat the water in 45 said heater, substantially as described.

12. In a stock-car, the combination of the following elements: the car-body provided with doors in the center of the sides and with 50 perforated side walls, inside sliding shutters applied thereto, with the contiguous shutters between the doors and ends of the car connected in series for joint operation, a device for holding each series of shutters in frictional contact against the side walls, vertical 55 folding stanchions hinged to the side walls, locking devices for holding said stanchions in position at right angles to the side walls of the car, independent coops adapted to fit between the stanchions, and projections on the 60 sides of the coops adapted to engage with the stanchions and form abutments between the coops in the adjoining rows, substantially as described.

In testimony whereof I affix my signature, 65 in presence of two witnesses, this 14th day of May, 1889.

JAMES NOLAN.
